UNITED STATES PATENT OFFICE

112,174

DESIGN FOR A FERRULE FOR UMBRELLAS OR THE LIKE

Louis Levine, Leominster, Mass.

Application August 29, 1938, Serial No. 79,624

Term of patent 3½ years

To all whom it may concern:

Be it known that I, Louis Levine, a citizen of the United States, residing at Leominster, county of Worcester, and State of Massachusetts, have invented a new, original, and ornamental Design for a Ferrule for Umbrellas or the like, of which the following is a specification, reference being had to the accompanying drawing, forming a part thereof.

In the drawing:

I claim:

The ornamental design for a ferrule for umbrellas or the like, as shown.

LOUIS LEVINE.
